UNITED STATES PATENT OFFICE

ANTHONY M. RINI, OF DOVER, OHIO

SEALING RING FOR JARS

Application filed December 28, 1927. Serial No. 243,073.

The present invention relates to improvements in sealing rings for preserving jars that are provided for the purpose of hermetically sealing the cover on the jar.

The usual rubber gaskets that constitute the sealing rings are difficult to grasp and pull outwardly whereby to break the seal and frequently a knife or other implement must be employed for disposition between the flange on the cover the jar and the sealing ring or shoulder of the jar so that the seal can be broken in order to facilitate the removal of the cover.

One of the important objects of the present invention is to provide a sealing ring which is of such construction as to enable the same to be pulled outwardly whereby to break to seal and at the same time uniformly distribute the strain around the elastic ring so that said sealing ring will not become broken or torn.

A further object of the invention is to provide a sealing ring wherein integral opposed lips are formed on the ring, said lips being formed with finger engaging shoulders that are curved at their inner faces to permit the fingers of the operator to readily grasp the lips and efficiently pull the sealing ring outwardly away from the jar so that the seal will be broken and the cover can then be readily and easily removed.

A still further object is to provide a sealing ring of the above mentioned character which is simple in construction, inexpensive, strong and durable and further well adapted to the purpose for which it is designed.

Other objects and advantages of the invention will become apparent from the following description taken in connection with the accompanying drawing.

In the accompanying drawing wherein like reference characters indicate like parts throughout the several views:

Figure 1 is a perspective view of the upper portion of an ordinary fruit jar showing my improved sealing ring in the act of being pulled outwardly to break the seal.

Figure 2 is a top plan view of the sealing ring.

Figure 3 is a cross sectional view therethrough, and

Figure 4 is a fragmentary detail of a modification of the lip structure.

In the drawing wherein for the purpose of illustration is shown the preferred embodiment of my invention, the numeral 1 designates generally my improved sealing ring, the same consisting of an annular body of elastic material. A pair of diametrically opposed lips 2 and 3, respectively, are formed integrally with the elastic annular body and extend from the peripheral edge thereof.

A shoulder 4 is formed on the upper face of each laterally extending lip at the outer edge portion thereof and as is clearly shown in Figure 2, the inner face of each shoulder is curved to conform to the contour of the thumb of the person grasping the sealing ring in the manner as clearly shown in Figure 1.

Furthermore, the outer edge of the shoulder conforms with the contour of the shape of the outer portions of each lip.

In Figure 4 of the drawing I have shown a modification wherein shoulders are formed on both the upper and bottom faces of each lip, said shoulders being designated by the numerals 5 and 6, respectively, and the inner faces of these shoulders are also curved to conform to the contour of the four fingers and thumb.

Normally, the sealing ring 1 is disposed around the threaded neck of the fruit jar A, and the screw threaded cover B will have its flange C engaging the upper face of the sealing ring and the bottom face of the sealing ring will be in engagement with the shoulder formed at the juncture of the threaded neck with the body of the jar, thereby forming a hermetically sealed jar. The lips will protrude beyond the edge of the flange so that the person can readily grasp either or both of the lips and by pulling the same outwardly, the seal will be broken and the strain will be evenly distributed around the annular member, thus preventing the ring from being torn. Furthermore, the provision of the shoulders on the outer edge portions of the lips will enable a person to more efficient-

ly grasp the lips and pull the same outwardly.

A sealing ring of the above mentioned character will at all times be positive and efficient in carrying out the purposes for which it is designed, and due to its simplicity, the same can be manufactured at a very low cost.

While I have shown the preferred embodiment of my invention it is to be understood that various changes in the size, shape and arrangement of parts may be resorted to without departing from the spirit of the invention and the scope of the appended claim.

Having thus described the invention, what I claim as new and desire to secure by Letters Patent is:—

A sealing ring consisting of an annular body of elastic material, an integral lip projecting from the peripheral edge of the annular body, and a shoulder formed on one face of the lip at the outer edge portion thereof, the outer edge of the shoulder being shaped to conform to the contour of the lip, the inner face of the shoulder being curved to conform to the contour of the finger or thumb of a person grasping the sealing ring and pulling the same outwardly.

In testimony whereof I affix my signature
30 ANTHONY M. RINI.
